RECOIL APPARATUS

William Summerbell, Watervliet, N. Y., and
Richard H. Mason, Havre de Grace, Md.

Application April 11, 1942, Serial No. 438,518

11 Claims. (Cl. 89—43)

(Granted under the act of March 3, 1883, as
amended April 30, 1928; 370 O. G. 757)

The invention described herein may be manufactured and used by or for the Government for governmental purposes without the payment to us of any royalty thereon.

This invention relates to recoil apparatus. An object of this invention is to provide a novel means for assembling a recoil spring on a firearm.

Another object of this invention is to provide a recoil spring coaxially mounted with the barrel of a firearm, whereby a firearm having a quick short recoil stroke is provided and the firearm is characterized by its small space requirements.

Another object of this invention is to provide novel means for mounting a recoil spring coaxially with a gun barrel and said novel means is characterized by its ease of assembly and disassembly.

The specific nature of the invention as well as other objects and advantages thereof will clearly appear from a description of a preferred embodiment as shown in the accompanying drawings in which:

Figure 1 is a side view, partly in section taken substantially on line 1—1 of Fig. 2 and discloses a preferred embodiment of our invention.

Figure 2 is a view taken substantially on line 2—2 of Fig. 1.

Figure 3 is a view taken substantially on line 3—3 of Fig. 1.

Figure 4 is a view taken substantially on line 4—4 of Fig. 1.

Figure 5 is a view taken substantially on line 5—5 of Fig. 1.

Figure 6 is a view taken substantially on line 6—6 of Fig. 1.

Figure 7 is a side elevation of the spring encasing member 17.

Figure 8 is an end elevation of the spring housing member 17.

Figure 9 is an end elevation of the spring housing member 18.

Figure 10 is a side elevation of the spring housing member 18.

Figure 11 is a section through the center of the washer or spring seat 19.

Figure 12 is a side view, partly in section taken substantially on line 12—12 of Fig. 13, and

Figure 13 is a view taken substantially on line 13—13 of Fig. 12.

The main elements of the assembly shown in Figs. 1—11 comprise a barrel B having a screw threaded portion 10 which cooperates with a corresponding screw threaded portion 11 on sleigh C having the pair of parallel guide mem-

bers 12, 12 and also integrally formed barrel encircling portion 13 coaxial with portion 11. Concave sleigh portion 14 spaces the integrally formed coaxial cylindrical portions 11, 13 and carries the hardened guide members 12, 12, by means of a welded connection or the guide members 12, 12 may be bolted to concave sleigh portion 14 by means of screws or bolts whereby the guides are replaceable.

The recoil cylinder D has a pair of parallel guide members 16, 16 cooperating with the sleigh guide members 12, 12 whereby the barrel B slides on the recoil cylinder D in recoil and counter-recoil.

The main and only recoil and counter-recoil spring E is coaxially mounted on the gun barrel B and held within the cooperating partial cylinders 17, 18 which form spring housings and which conveniently are joined together as by a bayonet joint or screw threads at their adjacent ends. The ends of spring E abut against shoulder 17a of member 17 and washer or spring seat 19 which may rotate with respect to encircling housing shoulder 18a. The spring seat 19 is made with an L-shaped cross sectional portion as shown in Figs. 1 and 11 with the horizontal portion 19a of the L abutting against sleigh C and the vertical portion 19b abutting spring E whereby compression forces are transmitted directly from the spring E to the sleigh C on barrel B.

Housing member 17 is joined to member 18 by inserting projections 17c into grooves 18d and simultaneously projections 18c into cut-out portions 17d and then turning said members approximately one-sixth of a revolution with respect to one another whereby projections 17c, 18c become aligned and coat so as to prevent relative axial movement of the housing members 17, 18.

The joined ends of members 17, 18 are locked in joined position by means of pin 20 which is inserted in a round cylindrical hole formed by hollow portions 17b, 18b in members 17, 18 respectively.

Flange 17e and the locking bolt head 20a on the joined ends of members 17, 18 are snugly received by cooperating recessed portions on the pair of snugly encircling supporting arms 21, 22 which are fastened to the recoil cylinder D by means similar to screws 23 and which also carry cylindrical trunnion members 24, 25. Also, bolts 30 join adjacent ends of the arms 21, 22 at the upper end. Trunnion members 24, 25 aid in rotatably supporting the assembly and also

trunnion 24 is adapted to carry sighting apparatus (not shown).

In firing operation the barrel B moves with respect to the recoil cylinder D which is fastened to a relative stationary part of the gun as by means of a key (not shown) adapted to fit into recess 26 and/or by means of fastening bolts entering the tapped portions 27.

The internal working parts in the recoil cylinder D are not disclosed other than the attaching part 29 which moves coextensive with the barrel B but comprise purely fluid means which serve the purpose of buffers at the end of the recoil, and/or counter-recoil strokes. In prior art structures, a mechanical spring similar to spring E was mounted in the recoil cylinder D and herein lies one phase of this invention, namely, transferring the recuperator spring E to a position coaxial with the barrel. Accordingly, the housing made up of the partial cylinders 17 and 18 is of small dimensions and a spring E having a diameter a little larger than the barrel diameter gives the gun a shorter recoil stroke and practically doubles the speed of normal operation.

In order to disassemble my preferred apparatus shown in Figs. 1-11, the barrel B is screwed out of engagement with cooperating screw threaded sleigh portion 11 and slid out of the encircling spring E. Upon removing screws 23, the spring assembly is separated from the recoil cylinder D by sliding the spring assembly relative to the recoil cylinder D on cooperating guide members 12, 16. Further when the spring assembly is completely removed from the recoil cylinder, clamping bolts 30 are removed, the pair of encircling members 21, 22 as well as pin 20 is removed, and the partial cylinders 17, 18 of the spring housing are rotated relative to one another approximately one-sixth of a turn whereupon the slightly prestressed spring E separates the members 17, 18.

In the assembly of my apparatus shown in Figs. 1-11, the spring E is prestressed within cooperating housing members 17, 18 and then said members are rotated relative to one another approximately one-sixth of a turn to bayonet joint holding position whereupon they retain the spring E without extraneous means.

When the gun is fired the barrel recoiling carries with it the sleigh C. The forward barrel encircling end 13 of the sleigh being in engagement with the sliding spring seat 19 will transmit the force of recoil to the pretensioned spring E whose other end is in engagement with the fixed shoulder 17a of the partial cylinder 17. This movement of the barrel will further compress the spring E and condition it to restore the barrel to battery position upon the cessation of the recoil force.

The main elements of the modified assembly shown in Figs. 12 and 13, comprise a barrel b which snugly engages circular portion 41 on sleigh c carrying the pair of parallel replaceable hardened guide members 42, 42 and also integrally formed barrel encircling portion 43 coaxial with portion 41. Concave sleigh portion 44 similar to portion 14 in the previous figures spaces the integrally formed coaxial cylindrical portions 41, 43 and carries the hardened guide members 42, 42 by means similar to screws 45 or by welding.

The recoil cylinder d has a pair of parallel guide members 46, 46 cooperating with sleigh

guide members 42, 42 whereby the barrel b slides on the recoil cylinder d in recoil and counter-recoil.

The main and only recoil and counter-recoil spring e is coaxially mounted on the gun barrel b and held between a fixed split cup-shaped support 47 and washer 49, Figure 12. The split cup-shaped supporting member 47 comprises a pair of barrel encircling portions or spring seat halves 51, 52 clamped together by bolts 48 and each of which is fastened to the recoil cylinder d by means similar to bolts 60. Each member 51, 52 carries a trunnion member 54, 55 which aids in rotatably mounting the barrel b and sighting apparatus (not shown).

In assembling the spring e, the washer or spring seat 49 and spring e are slipped over the barrel b after it has been inserted through sleigh portion 41 but before the barrel is inserted through sleigh portions 43. After the barrel b is inserted through the sleigh portion 43 and nut 61 is fully threaded on barrel threaded portion 62 the barrel encircling portions or spring seat halves 51, 52 are clamped around the barrel in the vicinity of sleigh portion 41 by means of bolts 48. Elongated screws (not shown) having heads thereon are passed through the auxiliary assembly holes 63 and pulled compressing spring e, and when holes 64 in the spring seat halves become aligned or nearly aligned with tapped holes 65 in the recoil cylinder, bolts 60 are inserted thus holding the spring e in compressed state. It is noted that the above movement of spring seats 51, 52 with respect to recoil cylinder d is guided by projections 66, 67 which snugly fit into grooves 68, 69 in the members 51, 52.

The internal working parts in the recoil cylinder d are not disclosed other than the attaching part 29 which moves coextensive with the barrel b but comprise purely fluid means which serve the purpose of buffers at the end of the recoil and/or counter-recoil strokes.

Also, it is understood that the spring seat 49 might be formed as an integral part of the sleigh portion 43.

In the modification just described the arrangement of the mechanism is substantially like that shown in the main figures. In this form the connection between the barrel and the sleigh is by means of the nut 61 threaded on the barrel as shown in Fig. 12. The front barrel encircling part 43 being in engagement with the sliding spring seat 49, will when the barrel recoils, transmit the force of recoil to the spring e, and the other end of the spring being in engagement with the fixed member 47, the spring will be conditioned to return the barrel to battery position upon the subsidence of the recoil force.

I claim:

1. A gun barrel, a coil spring encircling the barrel, a fluid control recoil cylinder, a barrel sleigh slidably mounted on the recoil cylinder, a movable spring seat on the barrel and moved in one direction by a sleigh portion, a nut threaded on the barrel in abutting relation to said sleigh portion, and a split spring seat detachably secured to the recoil cylinder and adapted to cooperate with the first mentioned spring seat so as to confine the coil spring therebetween.
2. A gun barrel, a relatively stationary gun part, a coil spring encircling the barrel, a barrel sleigh having a portion aligned with the barrel and slidably mounted on the stationary part, a spring seat abutting the aligned sleigh portion,

a nut threaded on the barrel and abutting the sleigh portion, said spring having one of its ends in engagement with said spring seat, and a second spring seat detachably secured to the stationary gun part at the other spring end.

3. The same as in claim 2 and the last mentioned spring seat comprises a split cup-shaped member.

4. The same as in claim 2 and the last mentioned spring seat being movable in guides formed on the stationary gun part and having holes therethrough adapted to receive assembly bolts.

5. A gun barrel, a spring assembly including a stationary part and a prestressed coil spring, said coil spring being mounted coaxially on the barrel with one of the spring ends engaging the stationary part, a stationary gun part, means for fastening together the first and second mentioned stationary parts, a barrel sleigh slidably mounted on the stationary gun part and including a portion thereof aligned with the gun barrel, means for fastening the gun barrel to the sleigh, and a movable spring seat engaging the other spring end and having a portion thereof projecting from the spring assembly in engagement with the aligned sleigh portion.

6. A spring assembly including: a casing, a prestressed coil spring having one of its ends engaging the casing, a movable spring seat engaging the other spring end and having a portion thereof projecting from the casing; a gun barrel, said spring being coaxially mounted with the gun barrel, a stationary gun part, a barrel sleigh slidably mounted on the stationary gun part, means for fastening the casing to the gun stationary part, means for assembling the barrel to the sleigh, and said spring seat projection abutting a portion of the barrel, sleigh assembly.

7. The same as in claim 6 and said casing comprises two modified cylinders joined at adjacent ends by a bayonet joint connection.

8. The same as in claim 6 and said casing comprising two modified cylinders joined at adjacent ends by a bayonet joint connection form-

ing a flange, means for locking the joined cylinder ends, said first mentioned means comprising a split hollow barrel encircling member snugly engaging and enclosing the flange and locking means, and said second mentioned means comprising a screw threaded connection between the barrel and sleigh.

9. A spring assembly including: a casing having a flange thereon, a prestressed coil spring within the casing and having one of its ends engaging the casing, a movable spring seat engaging the other spring end and having a portion thereof projecting from the casing; a gun barrel, said spring being coaxially mounted with the gun barrel, a stationary gun part, a barrel sleigh slidably mounted on the stationary gun part, a split barrel encircling member mounted on the stationary gun part and engaging the flange, said barrel and sleigh being assembled by a releasable connection, and said spring seat projection abutting a portion of the barrel, sleigh assembly.

10. In a recoil apparatus, a gun barrel, a portion fixed relative to the barrel, a fluid control cylinder having operative connections with said barrel, a sleigh upon which the barrel is slidably mounted, a spring seat carried by and slideable on the barrel and in engagement with said sleigh, a spring seat carried by said fixed portion, and a recuperator spring surrounding the barrel with its ends in engagement with said seats.

11. In a recoil apparatus, a gun barrel, a portion fixed relative to the barrel, a fluid control recoil cylinder having operative connections with said barrel, a sleigh by which the barrel is slidably mounted on the recoil cylinder, one part of the sleigh secured to the barrel and another portion thereof carried by and sliding on the barrel, a spring seat engaging the sliding sleigh portion and moved by the sleigh upon recoil of the barrel, another spring seat on said fixed portion and a coil spring surrounding the barrel with its ends against said seats.

WILLIAM SUMMERBELL.
RICHARD H. MASON.
